MICROTOME BLADE HOLDER

Robert E. Allen, Arlington, N. J., assignor to Custom Scientific Instruments, Inc., Arlington, N. J., a corporation of New Jersey

Application April 23, 1947, Serial No. 743,335

6 Claims. (Cl. 88—40)

1

My present invention relates to improvements in microtomes, that is, in apparatus for cutting specimens to thin slices for microscopic investigation. More particularly it relates to microtomes for the preparation of specimens of extreme thinness for ultra-microscopic examination, as for example, for the investigation of crystal lattice or atomic structures of metals and other materials.

The slicing of specimens to the thinness desired for this purpose (in some cases as thin as 0.1 micron or about 0.000004 inch) presents exceptional difficulties and is generally beyond the ability of slicing machines heretofore available.

In my present invention I provide a microtome carrying a slicing blade which moves at a high velocity, as for example, at a velocity of 500 to 600 feet per second, transversely of the specimen.

A slicing blade is rigidly mounted in radial position on a disc rotatable at a high speed, as for example, on a disc of about three and one-half inches in diameter to project radially one-quarter of an inch beyond the periphery of the disc. It is balanced by a blank so mounted on the disc as to provide an equal and opposite centrifugal force.

When a rod of the material to be sliced, and of a small diameter, as for example one-sixteenth of an inch, is moved slowly longitudinally and parallel to the axis of the disc against the blade while the disc is rotated at a high speed, as for example 70,000 revolutions per minute, slices of the specimen are cut to the desired thinness and may be caught on a suitable screen for microscopic investigation.

During rotation the blade must be supported and held without substantial vibration. The supporting disc has, therefore, a long hub for mounting on a coned spindle and tapers radially on a concave taper to a narrow margin in which the blades are mounted and secured. For this purpose a pair of slots are provided in balanced or diametrically in opposite positions in the edge of the disc, in one of which a knife blade is mounted and secured by a pair of screws and a clamping plate fitting into and opening through one face of the disc, and in the other of which a balancing blank is similarly mounted. One radial edge of the knife is sharpened toward the leading face against which the specimen stock is to be fed. This leading face may also slope away from the cutting edge by a slight angle, so as to clear the cut surface of the specimen.

The various features of the invention are ill-

ustrated, by way of example, in the accompanying drawings in which—

Fig. 1 is a side view and Fig. 2 an edge view of a rotor for mounting the cutting blades;

Fig. 3 is a detail view on a somewhat larger scale of a part of the rotor and cutting blade;

Fig. 4 is a view of a part of the rotor taken from the outer end of the blade;

Fig. 5 is a section on line 5—5 of Fig. 3;

Fig. 6 is a plan view, and Fig. 7 an end view of a cutting blade.

Fig. 8 is a view similar to that of Fig. 3 of a part of the disc in which the balancing blank is mounted.

In the embodiment of the invention shown in the accompanying drawings, a rotor 10 for carrying the blade may be mounted on a rotatable spindle 11 of tapered or coned surface on which it may be secured by a cap 12 and screw 13. The rotor 10 is widened at its central part to form a long hub portion 14 from which it tapers concavely as at 15 to a relatively thin edge margin.

The surface of the tapering part 15 is preferably concave inwardly on a line which in cross-section is of circular curvature. The curvature is such as to reduce the centrifugal force in the disc to a minimum and to maintain greater strength where the tension is greatest.

On diametrically opposite sides of the disc are provided slots for mounting a cutting blade or knife blade 16 and a blank 17. As shown more particularly in Figs. 3, 4 and 5 the blade is inserted radially into a slot 18 which extends inwardly a limited distance from the peripheral surface of the disc. This slot is somewhat larger in dimension than the blade and preferably one face 19 of the slot is on the median plane of the disc, that is, it is half way between the opposite faces of the marginal part. This leaves a relatively thinner wall 20 on one side and a relatively thicker wall 21 on the opposite side of the slot. An opening 22, preferably of circular formation, is formed in the thinner wall 20 and is filled with a plate 23. A recess 24 is similarly formed in the outer face of the thicker wall 21 and is filled with a plate 25.

The plates 23 and 25 and the wall 21 at the bottom of the opening 24 are provided with a pair of aligned openings transverse of the plane of the disc and centered on a radial line to receive a pair of screws 26 and 27. The openings in the plate 23 are tapped or threaded to mesh with the threads of the screws, while the openings in the wall 21 and plate 25 are of a size to permit the screws to pass through and rotate.

3

The part 28 of the knife 16 that is received in the slot 18 has a similar pair of spaced openings 29 and 30 through which the screws 26 and 27 extend. By screwing the screws into the plate 23 the plate may, therefore, be clamped toward the surface 19 and hold the blade securely in position.

The plates 23 and 25 will, of course, be flush with the parallel marginal surfaces of the disc.

The blade 16 has a part, indicated at 31, that projects beyond the periphery of the disc with a cutting edge 32. This cutting edge is somewhat in advance of the radial line of the disc on which the openings 29 and 30 are centered and is preferably advanced slightly beyond the leading edge of the part 28, as indicated at 33 in Fig. 3.

The cutting edge 32 is formed by grinding the leading edge on a plane 34 at an angle 35 of 30° or less and then on a larger angle 36. The face 37 of the blade against which the specimen is to be fed is also cut away at a slight angle 38 so as to clear the newly cut surface of the specimen.

The blank 17 is received in a slot similar to the slot 18 and on the diametrically opposite part of the disc. It is secured therein by a clamping plate, similar to the plate 23, and screws 39 as shown in Figs. 1 and 3. It is of sufficiently greater mass than the knife 16 to compensate for the projection of the knife blade beyond the edge of the discs and to provide a centrifugal force equal to that of the knife when the disc is rotated. The additional mass may be provided by making the blank of heavier material and of a larger size.

With each rotation of the blade a slice of the specimen may be obtained, the thickness of which may be controlled by the rate of feed of the specimen relative to the speed of rotation of the disc.

Having described the invention, what I claim is:

1. Microtome blade mounting disc having a hub to receive a spindle, an intermediate zone of decreasing thickness and a peripheral margin of relatively less thickness, said margin having slots extending from the periphery of said disc inwardly at balanced positions relative to said disc, said disc having openings, one for each slot, entering from one face to said slot, a plate in each said opening, said plate having a pair of tapped holes, and a pair of screws countersunk in the margin of said disc from the face opposite said opening and threaded into said tapped holes of said plate.

2. Microtome blade mounting disc having a hub to receive a spindle, an intermediate zone of decreasing thickness and a peripheral margin of relatively less thickness, said margin having slots at balanced positions extending from the periphery of said disc inwardly, said disc having

4

a recess in one face of said margin and an opening from the opposite face to said slot, a screw-holding plate in said recess, a clamping plate in said opening, said clamping plate having a pair of threaded holes, screws mounted in said plate and extending through said slot into the holes in said clamping plate.

3. The mounting disc of claim 1 in which said slots have one face in the mid plane of said disc.

4. The mounting disc of claim 2 in which said slots are at one side of the mid plane of said disc and in which said clamping plate enters from the face nearest said slot.

5. Microtome cutting element which comprises a blade mounting disc having a hub to receive a spindle, an intermediate zone of decreasing thickness and a peripheral margin of relatively less thickness, said margin having slots at balanced positions extending inwardly from the periphery, said disc having openings one for each slot, entering from one side face to said slot, a plate in each said opening, said plate having a pair of tapped holes, a blade for one of said slots having a shank mounted in said slot and having a pair of spaced openings aligned with the openings of said plate and having an extension beyond the periphery of said disc sharpened to a wedge edge at one side, and a pair of screws extending from the face of said disc opposite said opening through the holes in said blade and into the holes in said plate and a balancing blank in the other of said slots.

6. Microtome cutting element which comprises a mounting disc having a hub to receive a spindle, an intermediate zone of decreasing thickness and a peripheral margin of relatively less thickness, said margin having slots at balanced positions extending inwardly from the periphery of said disc, said slots being at one side of the mid plane of said disc, a cutting blade having a shank portion mounted in one of said slots and projecting beyond the periphery thereof, means to secure said blade in said slot, the projecting part of said blade being sharpened to wedge shape toward the mid plane of said disc and the side face near said sharpened edge being cut away at a slight angle from the mid plane of said disc.
